ATTORNEY

UNITED STATES PATENT OFFICE

CHARLES M. BOLINGER, OF ST. LOUIS, MISSOURI

CLOTHES HANGER

Application filed January 21, 1928. Serial No. 248,480.

This invention relates to garment hangers which embodies among other characteristics a supporting hook adapted to be folded upon the hanger to minimize space within wardrobe trunks and the like, or when not in use and packed for transportation.

Another object of the invention embodies a locking element adapted for use in conjunction with the supporting hook to prevent displacement of the hook upon a hanger rod.

An additional object of the invention comprehends rod members adapted for detachable engagement with the hanger to facilitate the insertion of pants, plaited skirts and the like therebetween and which when lockingly engaged with the hanger will preserve creases within garments.

More specifically stated, said arms are provided with a common locking element which when disengaged from said arms will permit removal of the pants from the hanger thereby obviating the usual necessity of removing a coat, vest, etc. from the hanger precedent to the removal of the pants therefrom.

With the above and other objects in view, the invention further consists of the following novel features and details of construction, to be hereinafter more fully described, illustrated in the accompanying drawing and pointed out in the appended claim.

In the drawing:

Figure 1 is an elevation of the invention.

Figure 2 is a sectional view taken on line 35 2-2 of Figure 1.

Figure 3 is a sectional view taken on line 3-3 of Figure 1.

Figure 4 is a sectional view taken on line 40 4-4 of Figure 1.

Figure 5 is a sectional view taken on line 5-5 of Figure 1.

Figure 6 is a sectional view taken on line 6-6 of Figure 1 through the locking element for the supporting hook.

Referring to the drawing in detail, wherein like characters of reference denote corresponding parts, the reference character 10 indicates a hanger formed of a length of wire bent upon itself at one end as indicated at 50 11 to provide an upstanding loop 12. The op-

posed end of the hanger is bent upon itself to provide spring convolutions 13; the extremity of said convolutions terminate in arms 14 adapted for reception within the looped end 11 of the hanger.

The intermediate portion of the hanger has formed a spring loop 15 between the convolutions of which is extended a supporting hook 16. The supporting hook is also doubled as best illustrated in Figure 2 of the drawing.

A locking element for the supporting hook is in the nature of arms 17 pivotally connected, as indicated at 18 at the innermost ends thereof and which terminate to provide, at their opposite ends, heads 19 adapted to be extended through the thicknesses of the supporting hook 16; the heads 19, after being forced between said thicknesses will release the latter which will spring against the arms 17 proper immediately behind said heads which will then be held against displacement. Such construction allows the supporting hook to be lockingly engaged with a hanger rod, not shown, and which will prove highly effective in 75 wardrobe trunks wherein the hangers are subjected to sliding movement.

A guide 20, slidably mounted upon the convolutions of the loop 15, is provided with a central opening through which the thicknesses of the hook 16 extend. The hook 16 through the sliding action of the guide 20 may be shifted to occupy a position in juxtaposition to the hanger per se.

A brace 21, carried by the hanger 10, is provided with a loop 22 upon the uppermost end thereof projected within the loop 15 and adapted for pivotal connection with the lowermost end or ends of the supporting hook 16.

A hook 23 mounted for lateral swinging movement upon the brace 21 is adapted to support head coverings, ties, etc. A stiffening brace 24, having connection at one end with the upstanding loop 12, is extended through a loop portion 25 in the lowermost end of the brace 21. A link 26, having connection with the convolutions 13, is adapted for locking engagement with the remaining and adjacent end of the stiffening brace 24.

A locking element, embodying a length 100

of wire 27, bent upon itself to provide an up-standing portion 28 offset from ears 29, is adapted to engage the intermediate bent portion 11 of the hanger 10. The extremities of the arms 29 are looped, as indicated at 30, around the thicknesses or plies of the hanger. The extremities of the arms 14 will thus be held against displacement when in wardrobe trunks or other movable containers. The locking element, aforementioned, will release the arms 14 when shifted outwardly toward one end of the hanger and slid upwardly an appreciable distance thereon.

The invention is susceptible of various changes in its form, proportions and minor details of construction, and the right is herein reserved to make such changes as properly fall within the scope of the appended claim.

Having described the invention, what is claimed is:—

20 A garment hanger comprising a length of wire bent upon itself at one end and forming multiple spring loops at an intermediate point, a guide slidably mounted upon the 25 spring loops, and a supporting hook slidably connected with the guide to occupy an out of the way position.

In testimony whereof I affix my signature.

CHARLES M. BOLINGER.
